UNITED STATES PATENT OFFICE

2,655,837

AUTOMATIC GUN

Melvin M. Johnson, Jr., Brookline, Mass., assignor
 to Melvin M. Johnson and Melvin M. Johnson,
 Jr., trustees of the Johnson Patent Trust,
 Boston, Mass.

Application September 16, 1947, Serial No. 774,310

18 Claims. (Cl. 89—33)

1

This invention relates to firearms of the rapid firing portable type such as is shown and described in United States Patents Nos. 2,094,156; 2,146,743; 2,215,470; and 2,383,487, granted upon applications filed under my name, and the objects of the present invention are to improve the aforesaid gun in several aspects to provide for smoother operation and greater efficiency without sacrificing any of the features and advantages of that gun. More particularly, these objects include the provision of improved cartridge-feeding means, which is simple and economical in construction, which is reliable and durable in use, which can be assembled and disassembled with ease, and which is especially suitable for supplying cartridges to the gun by way of a disintegratable type of cartridge-feed belt; of improved breech bolt locking means to insure locking of the bolt in a closed position; of improved ejector construction to prevent destruction of the extractor during ejection; and of improved firing-pin mechanism to prevent premature firing.

As illustrated herein, the gun is of the recoil-ing barrel type including a receiver, a barrel mounted for recoil and counter-recoil therein, the barrel having a breech and cartridge chamber and a bolt and bolt chamber, the latter being in the receiver. Below the bolt chamber there is detachably secured, in accordance with this invention, a cartridge feed-in mechanism arranged intermittently to feed a belt of cartridges inwardly from one side of the gun to present one cartridge at a time into a position to be rammed by the bolt into the cartridge chamber. The feeding mechanism is motivated, in accordance with one aspect of this invention, by the recoil of the barrel in contrast to the conventional use of the bolt for this purpose, thus providing for more positive operation because of the greater weight of the barrel and for use of this type of feed-in, in light-weight guns wherein the kinetic energy imparted to the bolt is not sufficient to actuate the feed mechanism. In another aspect it is contemplated to supplement the energy of the barrel in recoil because its recoil is comparatively short with some of the energy of the gases generated by the explosion of the cartridge by conducting part of these gases to a piston-like member on the barrel, thereby to impart additional force to the recoil of the barrel. As illustrated, a cylinder is formed on the receiver, gas is supplied thereto from the barrel through a small aperture in the wall thereof, and a piston is formed on the barrel which fits closely into the cylinder.

2

The feed mechanism includes pairs of feed pawls operable successively by the recoil of the barrel to engage cartridges in the cartridge belt and to move them one at a time onto an elevator below the bolt chamber, each pair of pawls after moving a cartridge a predetermined amount being retracted beneath the succeeding cartridge to engage the rear side thereof for the next forward feeding movement. A narrow passage in the bolt chamber allows a portion of the cartridge on the elevator to project into the path of the bolt.

As constructed, the feed mechanism is housed in a feed mechanism housing, and for ease of assembly the latter is slidably mounted in the receiver in cooperating ways. By taking up of its position in the receiver cooperating elements on the housing and receiver are operably engaged to connect the feed mechanism for the pawls to the barrel for operation thereby. The housing has an upper throat-like portion through which the cartridge belt is fed by the aforesaid pawls, the latter projecting upwardly into the throat from an enclosed lower portion in which the feed pawl operating mechanism is located. This operating mechanism is carried by a movable support therein which may be retracted within the housing to withdraw the pawls from the feedthroat, thereby to clear the throat so that the cartridge belt may be removed. A retaining pawl in the top of the throat cooperates with the pawls normally to hold the belt against retrogression, and this, too, may be retracted to clear the throat.

The aforementioned breech bolt has splines at its forward end which enter the breech block through spline-ways and is rotated to move the splines to a position between the spline-ways of the breech block, thereby to lock the bolt in breech-closing position. To prevent partial or complete unlocking of the bolt as it is rotated into locking position due to rebound, there is, in accordance with this invention, an independent, spring-loaded lock cooperable with a recess in the bolt opposite which it is brought by rotation of the bolt so that counter-rotation of the bolt is prevented. As constructed, the lock may be manually lifted out of the recess to unlock the bolt or automatically removed therefrom by the combined recoil of the barrel and bolt.

The breech bolt is hollow, that is, has a longitudinal passage therein in which there is situated a firing pin. A spring normally holds the firing pin withdrawn in the bolt so that when the bolt is in breech-closing position the firing pin does not project. Due to the fact that

the forward movement of the bolt and firing pin is rapid, when the bolt is brought to a sudden stop, momentum of the firing pin throws it forward in spite of the spring so that there might be an accidental firing of the cartridge. Hence, in accordance with this invention, there is a slot formed in the firing pin and a stop in the bolt projecting into this slot which limits the movement of the firing pin so that it can not move out of the end of the bolt before the bolt is locked in position. The bolt is made up of two pieces arranged end to end, the adjacent ends of which have cooperating cam surfaces. During movement of the bolt toward bolt-closing position, cooperating means on the bolt and receiver hold the parts in an extended position. As the bolt moves into bolt-closing position, however, the forward piece is released, whereupon the rear piece imparts rotation to the forward piece, thus shortening the effective length of the bolt. In its shortened state, the aforesaid slot is long enough to permit the firing pin to be projected beyond the end of the bolt by the blow of the hammer.

The bolt has an extractor thereon which pulls the empty case from the cartridge chamber in recoil, and there is, in accordance with the usual practice, an ejector mounted on the receiver in a position to intercept the cartridge case as it is retracted and to tip it about the extractor hook and out through an ejection port. The shock of the impact of the case against the ejector tends to throw it forward about the extractor in such a fashion as to rupture the latter. To minimize this rupturing force the ejector has, in accordance with this invention, a cushion head for receiving the impact of the cartridge, thereby to reduce the shock. As illustrated, the head is pivoted on the ejector and is held in a forward position by springs.

The invention will now be described in detail in its various aspects with reference to the accompanying drawings.

Fig. 1 is a longitudinal, vertical section through a firearm of the recoiling barrel type showing that portion between the trigger and the midpoint of the barrel embodying the various features of the invention with the cartridge feeding unit unsectioned to show its relative location with respect to the operating parts of the gun;

Fig. 18 is a transverse section on the line 16-16 of Fig. 14 showing the bolt rotated to an unlocked position; and

Fig. 19 is a longitudinal section on the line 18-18 of Fig. 18.

As illustrated in Figs. 1 and 2, the gun comprises in general a receiver 10, a barrel 12 and a stock 14. The receiver has formed integral with the forward portion thereof a sheet metal radiator sleeve 16 which is provided with perforations 18 to facilitate dissipation of the heat to keep the barrel cool, particularly during automatic use, the shield also forming a protecting guard to prevent contact of the hands with the barrel. The gun is supported at approximately the mid-length of the barrel by a monopod 20, the construction of which is disclosed in United States Patent No. 2,386,802, pivoted to a spacer member 22 which is fastened beneath the barrel between depending flanges formed at the underside of the sleeve 16, as also disclosed in the aforementioned patent. The stock 14, Fig. 2, is mounted at the rear portion of the receiver and includes a trigger guard 26 and trigger-actuating mechanism which is not shown herein since it does not form a part of the present invention.

The barrel 12 is slidably mounted within the receiver and has a cartridge chamber 28 at the rear end portion thereof and a breech block 30, the latter being slidable in a bearing 32 formed internally of the receiver and providing a support for the rear end of the barrel. The forward end of the barrel is supported midway of its length by an enlarged bearing portion 34 slidably fitting within a bearing sleeve 36, the latter bearing in the forward end of the radiator sleeve. A head 38 is formed on the bearing sleeve to provide a surface for locking the barrel in position. To prevent accidentally jarring loose of the bearing sleeve 36, a lock block 40 is slidably set into a vertical opening 42 formed in the spacer 22 ahead of the monopod and is yieldably held by a spring 44 in a position in front of the head 38 to prevent longitudinal movement thereof. The lock block may be depressed against the spring to disengage it from the head 38 of the sleeve, and may be held depressed by engagement of a groove 45 therein with a split ring 46.

The bearing portion 34 is cylindrical and together with the bearing sleeve 36 forms a piston and cylinder for a purpose which will appear hereinafter. Forward movement of the barrel in counter-recoil to battery position is limited by an annular shoulder 48 formed at the rear end of the piston-like portion 34 for engagement with the rear end of the cylinder-like bearing sleeve 36. Rearward movement of the barrel during

recoil is limited by an annular surface 50 formed in the receiver against which the breech block is driven in recoil. Behind the barrel and breech block in the receiver there is a bolt chamber 52 in which there is slidably mounted a breech bolt 54 for movement in recoil and counter-recoil. Below the bolt chamber 52 and between trigger guard 26 and the breech block there is disposed a cartridge-feeding unit 56 which is adapted, as will appear hereinafter, to feed cartridges 57 (Fig. 3) one at a time into a position to be rammed into the cartridge chamber 28 by the bolt 54. The cartridges 57 are assembled in belt form by means of a disintegratable type of link 59 (Fig. 9), the belt being fed in from one side, that is the left side, of the gun as seen in Fig. 4 and the disconnected links being discharged at the opposite side. The cartridge-feeding unit 56 includes pairs of feed pawls 58 and 60 which are adapted to engage the cartridges of the belt and to move them step by step into a position beneath the bolt chamber 52 and to present them in such a position that the upper portion thereof projects through an opening 62 (Fig. 4) in the lower wall of the bolt chamber.

Cartridge feed unit

The cartridge-feeding unit 56 (Fig. 4) is provided with means for alternately advancing and retracting the feed pawls 58 and 60 which is operated through the recoil of the barrel 12, as will now appear. Formed on the breech block 30 (Figs. 1 and 2) is a shoulder 64. In engagement with this shoulder 64 is a lug 66 projecting upwardly from a block 68 apertured to receive through it a rod 70 and being fixed thereto by a pin 72. The rod 70 is slidably mounted in a channel 74 formed in the underside of the spacer 22. Below the spacer and closing the channel formed therein, through which the rod moves, is a cover plate 76 pivotally supported on the receiver at its rear end at 78 so that it may be tilted downwardly to provide for easy access to the slide rod for inspection thereof. The forward end of the cover plate is supported in position by a latch 80 pivotally supported at 82 on the spacer 22 and yieldably held in latching position by the spring-pressed ball 84. The rod 70 passes through an aperture 86 formed in a downwardly projecting web 88 at the rear end of the spacer 22 and between this web and a collar 90 fastened to the forward end of the rod there is disposed on the rod a coiled spring 92. The spring serves to hold the rod in a forward position, and hence through the lug 66 and shoulder 64 to hold the barrel in battery position, that is, with the shoulder 48 engaged with the rear end of the sleeve 36. The rear end of the rod is provided with a T-shaped head 94 which, as will appear hereinafter, provides for a quickly detachable slidable connection between the rod and the mechanism within the cartridge-feeding unit 56.

The movement of the barrel 12 in recoil is short and hence it is desirable to add to the recoil force of the barrel some of the expansive force of the gases generated within the barrel after the cartridge has been exploded and prior to the time at which the slug leaves the end of the barrel. Hence, there is formed in the barrel just ahead of the piston-like portion 34 an aperture 96 from which these gases may escape into the cylinder 36 behind the piston 34 so as to force the piston rearwardly to add to its force of recoil.

The cartridge-feeding unit 56 comprises (Fig. 4) a two-part feed mechanism housing consist-

ing of an upper part 98 and a lower part 100 hinged along one longitudinal edge at 102 to provide a housing which in cross-section is substantially ovaloid and in which any longitudinal section is substantially rectangular. The top wall of the portion 98, however, has spaced above it a wall 104 to provide a transverse throat or passage 106 having end walls 108 and 110, as shown in Fig. 6. The top wall 104 terminates in a bent back portion 112 and the side walls 108 and 110 are flared outwardly at 114 and 116, respectively, and turned back upon themselves, thereby to provide for a smooth, flaring mouth or entrance to the passage 106.

The top wall of the portion 98 of the housing has an aperture 118 (Fig. 4) therein through which the feed pawls 58 and 60 project. As illustrated, the feed pawls advance the cartridges inwardly through the passage 106 and push one cartridge at a time onto an elevator 120 which is pivotally mounted on the top wall of the portion 98, the elevator being adapted to raise the cartridge and hold it in such a position that the upper portion thereof projects through the opening 62. As shown in Fig. 6, the elevator 120 consists of a narrow plate 122 having a longitudinal depression 124 therein in which a cartridge is adapted to rest and which will prevent side slip of the cartridge on the plate when pressure is applied. The rear portion of the plate 122 has extending laterally therefrom at opposite sides aprons 126 and 128. The apron 126 is inclined downwardly and occupies a position between the pawls 60 so that as a cartridge is advanced by the pawls it is pushed into engagement with the apron 126, thereby depressing the apron during movement of the cartridge into a position in the depression 124. The elevator is pivotally supported on a block 130 (Fig. 10) which is fastened in an upright position to the upper wall of the portion 98, the block having rearwardly extending spaced bosses 132 which are apertured to receive a spindle 134. A pair of arms 136 project rearwardly from the elevator 120 and are apertured to receive the spindle 134, thereby pivotally supported the elevator in position. A spring 138 is mounted on the spindle in a position yieldably to hold the elevator in an elevated position. The elevated position of the elevator is limited by surfaces 140 (Fig. 4) formed on the undersides 50 of the arms 136 which abut the upper wall of the portion 98, as shown in Fig. 4. The apron 128 at the rear side of the elevator forms a smooth surface over which may be ejected the disintegrated elements of the cartridge belt.

Within the feeding unit housing 56 (Fig. 12) there is a slide plate 142 having a T-slot 144 therein (Fig. 3) which may be coupled with the T-head 94 formed on the rod 70 merely by mounting the case in the receiver, the T-slot 144 being open at one side to receive the T-head 94. The slide plate 142 is reciprocated by the barrel through the distance indicated in Fig. 3 by the dot-and-dash line, and this reciprocatory movement affords the motion necessary to oscillate the feed pawls, as will now appear. The slide plate 142, as shown in Fig. 12, is mounted within the housing against the inside of the top wall of the portion 98 for sliding movement on a pair of spaced pins 144 which project downwardly from the top wall through slots 146 formed in this plate, the pins having heads on their lower ends which retain the plate in position. The plate 142 has at the right side thereof, as shown in Fig. 12, an open slot 148 formed therein which

embraces a pin 158, the latter being fixed to a leg 152 of a T-shaped member 154. The T-shaped member 154 is pivotally supported midway between the ends of its head on a pin 156, the pin being secured to the upper face of a table 158 (Fig. 5). A flat plate 160 is mounted on the table 158 for sliding movement thereon, being held in position thereon by a slot 162 (Figs. 6, 12 and 13) formed in the plate which embraces a pin 164 fixed in an upright position to the table. This plate 160 has, as shown in Fig. 12, a forwardly projecting limb 166 which is pivotally connected to one end of the head of the T-shaped member 154 by a pin 168. There is also mounted on the support 158 and above the plate 160 a second flat plate 170, this plate also having a slot 172 formed therein which embraces the pin 164 so as to limit its movement and to guide it. A forwardly projecting limb 174 formed on this plate is pivotally connected to the opposite end of the head of the T-shaped member 154 by a pin 176. It is evident, therefore, that by oscillation of the T-shaped member 154 about its pivot point 156 the plates 160 and 170 may be made to reciprocate relative to each other. To take up any slack in the parts a hair-pin spring 178 (Fig. 13) is pivotally fixed to the pin 156 and has its ends respectively fixed to the leg of the T-shaped member 154 and the table 158 by pins 180 and 182.

Formed integral with the flat plate 160 (Fig. 4) are a pair of spaced upright posts 184 in which there are supported pins 188 on the ends of which are pivotally mounted the pawls 60. Corresponding upright posts 190 are fixed to the flat plate 170 between which is mounted a spindle 192 upon which are pivotally mounted the pawls 58. It is evident from this construction that oscillation of the plates 160 and 170 will produce a corresponding oscillation of the pawls 58 and 60. The pawls 58 and 60 are yieldably held in a position projecting through the aperture 118 in the top wall of the portion 98 by means of springs 194 and 196 (Fig. 4) interposed between pawls and the plates 160 and 170, respectively. As constructed, the pawls 58 and 60 have slightly convex forward faces so that they embrace a substantial portion of each cartridge, and as they are reciprocated they move the cartridges in two steps into position, one pawl being retracted beneath the succeeding cartridge while the other pawl is advancing the yieldable springs permitting the retreating pawl to be depressed by the succeeding cartridge.

The table 158 is provided with a pair of spaced bosses 198 at one end thereof, as shown in Fig. 4, by which it is pivotally supported so that it may be drawn down to the dot-and-dash line position to withdraw the feed pawls from the throat 106 so that the cartridge belt may be removed if this is necessary. To this end a pair of pivot pins 200 and 202 are provided for engagement with apertures formed in the bosses 198. The pivot pin 200 is fixed, being formed on the inner end of a pin set into one wall of the housing, as shown in Fig. 12. The other pin 202 is yieldably held in the aperture in the boss 198 so that it may be retracted if it is desirable to permit removal of the table 158. To this end pin 202 has a stem 204 which extends through an aperture 206 formed in a web 208 projecting inwardly from the wall of the housing and formed integral therewith. The rear end of the stem 204 is reduced at 208 and occupies an aperture 210 formed in a second web 212 projecting into the housing. A spring 214 surrounding the pin and interposed

between the webs 212 and 208 yieldably holds the pin in the aperture of the boss 198. This is accomplished through the medium of a U-shaped lock 216 which straddles the web 208 and has slots in its legs which in turn straddle the stem 204, the latter having spaced grooves therein cooperating with the straddling legs to limit longitudinal movement of the pin. The spring 214 bears against one leg of the U-shaped lock 216.

In order to draw the table 158 down into the dot-and-dash line position shown in Fig. 4, there is formed in the rear end thereof at opposite edges a pair of slots 218 which are adapted to receive spaced pins 220 fixed in the upper ends of a pair of spaced arms 222 (Figs. 4 and 12). The spaced arms 222 are joined by a bridge piece 224 to form a rigid, yoke-shaped member which is pivoted for rocking movement on a shaft 226 which passes through the lower ends of the arms. As shown in Fig. 12, the shaft is journaled at one end in spaced webs 228 projecting upwardly from the bottom portion 100, and at the other end in the side wall thereof. The shaft 226 extends through the wall of the portion 100 and has fixed to the outwardly projecting end thereof a lever 230 (Figs. 6, 10 and 11) so that by rotation of the lever the yoke-shaped member may be rocked from the full line position shown in Fig. 4 to the dot-and-dash line position, thereby to draw the table 158 downwardly. The table 158 is normally locked in its operative position by the yoke through the intermediary of the lever 230 as follows: In the lever 230 there is formed a recess 232 (Figs. 10 and 11) within which there is disposed an arm 234, the latter being pivotally fixed therein by means of a pin 236. The arm has a head 238 by which it may be grasped and moved about its pivot point. Inwardly of the head 238 is a shoulder 240 which is adapted to occupy a recess formed in the wall of the housing. As thus constructed, when the arm 234 is pushed inwardly so that the shoulder 240 occupies the recess in the wall of the housing, the lever 230 is restrained from pivotal movement. If the arm 234 is pulled outwardly to disengage the shoulder 240 from the recess, the arm 234 is free to rotate and hence may be rotated to move the table 158 downwardly.

Cooperating with the feed pawls there are retaining means in the form of pairs of spaced pawls 233 which are pivotally mounted adjacent to an opening 235 formed in the top wall 104 of the throat, having inwardly projecting ends 237 adapted to engage behind a cartridge in the belt of cartridges to prevent accidental slipping of the belt rearwardly. The pawls are pivotally mounted on a common pin 241 fixed at its ends in a bracket 243 formed in the top wall 104. One pair of the pawls is shorter than the other and they are partially independent of each other, the shorter ones being yieldably urged downwardly by a spring 243. As constructed and shown in Fig. 4 the longer pawls are engaged with the rear side of a cartridge and hence operate to hold the cartridge belt against retrograde movement. The shorter pawls rest against the top of the succeeding cartridge. As the belt is advanced, however, the longer pawls will rise by engagement with the succeeding cartridge and will have no restraining effect on the belt. Hence, during this period the shorter pawls will be urged downwardly behind the cartridge, and will effectively hold the belt against rearward movement until the longer ones of the pawls become effective again. When it is desirable to remove

the belt, the pawls may be withdrawn by depressing the upper outwardly projecting arm 239 thereof. Lifting of the shorter pawl is effected by engagement of the surface 245 on the under side of the arm 239 with the top surface 247 of the short pawl.

The two portions 98 and 100 of the housing are normally held locked together by means of a releasable latch. As shown in Figs. 5 and 8, there is fastened to the upper portion 98 a channel-shaped bracket 242 having a ledge 244 at its lower end with which there is engaged a latch member 246. The latch member 246 is pivotally secured by a pin 248 to a block 250 fixed to the bottom wall of the portion 100, and has a lateral extension 252 from which projects a knob 254. An aperture 256 is formed in the bottom wall of the portion 100 opposite the knob 254 so that an end portion thereof projects through the wall. A spring 258 mounted on the pivot pin 248 yieldably holds the latch in latching position. By pressure on the knob 254, however, the latch may be disengaged from the ledge 244 so that the lower portion 100 of the housing may be swung downwardly about the hinge 102 to permit inspection and repair of the feeding mechanism without dismounting the housing from the gun.

The housing 56 is held in position on the receiver by a forwardly projecting tongue 260 which, as shown in Fig. 3, is formed on a plate 262 fastened to the forward wall of the housing. This tongue is adapted slidably to engage a transverse slot 264 formed in the rear end of the cover plate 76. The rear end of the housing (Fig. 6) is supported by a rearwardly projecting tongue 266 and spaced vertical flanges 268. As shown in Fig. 1, the tongue 266 occupies a horizontal, transverse slot 270 formed in the forward portion of the trigger guard 26, and the flanges 268 straddle the opposite sides of the guard. It is to be observed that the stock 14, together with the guard, are mounted on the receiver after the housing is slid into its proper position. To prevent sidewise movement of the housing at its forward end, after it is seated in its proper position, a bail 272 (Fig. 3), pivotally supported on the receiver at 274, is arranged to be swung over the forwardly projecting tongue 260 to hold it in place. It is evident that after the stock is removed the housing may be mounted and dismounted merely by sliding it transversely into and out of the receiver, no bolts or other threaded members being necessary to secure it in place.

Operation of cartridge feed unit

In operation when a cartridge is fired from the gun the barrel 12 moves rearwardly in recoil, and simultaneously the rod 70 moves rearwardly by reason of the engagement of the shoulder 64 with the lug 60. Rearward movement of the rod 70 is communicated to the plate 142 by way of the T-connection 94—144 to move the plate rearwardly, that is, as shown in Figs. 6 and 12, downwardly. The movement of the plate 142 in turn imparts movement to the T-shaped member 154, causing it to pivot about the pin 156 in a clockwise direction by reason of the rearward movement of the leg 152 which is connected to the plate by a slot and pin 148 and 150. Clockwise movement of the T-shaped member causes movement of the plate 160 to the left and the plate 170 to the right, as shown in Fig. 12, and since these plates carry the pawls, the pawls 60 are moved toward the left, at which time they yield downwardly and pass be-

low the cartridge immediately behind them, and the pawls 58 move toward the right to advance the cartridge part way toward the elevator. Upon counter-recoil of the barrel to battery position, produced by the heavy spring 92, the rod 72 moves forwardly, thereby moving the plate 142 forwardly. This reverses the rotation of the T-shaped member 154, and hence the movement of the pawls so that now the pawls 58 are retracted toward the left and the pawls 60 advanced toward the right to pick up the cartridge partially advanced by the pawls 58 and to move it on to the elevator. The cycle of operation is then complete and may be repeated as often as is desirable, depending upon whether the rifle is being operated in automatic or semi-automatic fire. As the cartridge is advanced onto the elevator, it is raised into position to be picked up by the bolt, and as the cartridge is disengaged from the links of the belt, which, as heretofore described, is of the disintegrating type, the link holding the cartridge is released from the succeeding link and is ejected laterally from the opposite side of the housing.

Breech bolt lock

As constructed herein (Fig. 3), the bolt 54 is provided at the forward end thereof with splines 276 which are adapted to slide through correspondingly spaced splineways 278 formed on the inner surface of the breech block 30 as the bolt moves into breech-closing position, and after the splines clear the splineways to be rotated into a position in which the splines lie between the splineways, thereby to lock the breech bolt in closed position. Rotation of the breech bolt is accomplished as follows: Referring to Fig. 15, the breech bolt is illustrated as comprising two sections 280 and 282 which are arranged end to end, at least a portion of one being in telescoping engagement with the other, and having on their adjacent end cooperating raised cams 284 and 286. The cams 284 and 286 have engaging cam surfaces 288 and 290 (Fig. 14). In the top, inner surface of the bolt chamber there is a longitudinal groove 292 (Fig. 16) within which the cams 284 and 286 move as the bolt moves in recoil and counter-recoil. During the greater part of the movement of the bolt this groove holds the bolt in such a position that the splines 276 will enter the splineways 278. As the bolt enters the breech block, the splines 276 clear the splineways and the forward portion 282 of the bolt is caused to rotate by the force of the rear part 280 through the engagement of the cam surfaces 288 and 290. Rotation of the forward section is permitted by entrance of the cam 286 into a lateral enlargement 294 of the groove 292. Once the bolt has been rotated to locking position, it is desirable, to prevent counter-rotation thereof which may be caused by rebound, to have independent locking means to prevent such counter-rotation. As illustrated (Fig. 17) this independent locking means comprises a lever 296 pivoted at 298 in a recess 300 on the receiver. One end 302 projects from the recess for engagement by the thumb of the operator to release the lock, as will appear hereinafter. The inner end 304 of the lock has a tongue 306 thereon which projects through a hole 308 in the receiver into engagement with the surface of the bolt. During forward movement of the bolt to locking position, the tongue 306 rides on the surface of the bolt until the bolt is rotated into locking position, as heretofore indicated, and at this time it is forced down-

11

wardly into a recess 310 formed in the bolt (Fig. 16) by means of a spring 312 disposed between the outer end 302 of the lever and the receiver on a pin 314 fixed to the lever 296. The tongue 306 will, therefore, prevent counter-rotation of the bolt, and hence it can not be unlocked and forced rearwardly by the explosion of the cartridge prematurely. To release the bolt the lever 296 may be depressed to lift the tongue 306 from the recess 310, whereupon the bolt may be rotated by means of a finger lever 316 (Fig. 14) to an unlocked position (Fig. 18). Thereafter, by pulling rearwardly on the finger lever 316, the bolt may be drawn rearwardly in the receiver to a cocked position. The bolt, in automatic operation of the gun, is unlocked by the recoil of the barrel and bolt as follows: Referring to Figs. 17 and 19, it is to be observed that, during the initial part of the recoil, the barrel and bolt move as a unit relative to the lever 296 which moves the recess 310 rearwardly with respect to the tongue 306. The recess has an open end opening onto a reduced cylindrical portion 318, as shown in Fig. 19, so that when the tongue moves out of the recess onto this cylindrical position the bolt is free to rotate. Simultaneously with the movement of the tongue 306 out of the recess onto the cylindrical portion 318, as shown in Fig. 19, the cam 286 causes rotation of the part 282 in a clockwise direction, as shown in Fig. 18, this being brought about by engagement of a cam surface 320 on the cam 286 with a cam 321 Fig. 16 on the inside of the bolt chamber. The cam surface 320 and cam 321 on the inside of the bolt chamber cooperate to rotate the part 282 sufficiently so that both the cams 286 and 284 are again aligned with the cam groove 292, hence rearward movement of the bolt in its correct position is assured.

Operation of breech bolt lock

In operation, as the bolt moves forward in counter-recoil, for example in fully automatic fire, the cams 284 and 286 hold the two parts of the bolt 280 and 282 in alignment so that the splines 276 pass through the splineways 278 in the breech block. As the bolt is thrust home, the splines clear the splineways and the cam 286 reaches the lateral enlargement 294 and is, therefore, no longer restrained from rotational movement. The momentum of the parts is such that the rear part 280 exerts rotational force on the forward part 282 through the intermediary of the cam surfaces 288 and 290 to rotate the forward part 282 into a locking position. Simultaneously the tongue 306 is thrust into the recess 310 by the spring-actuated lever 296 so that counter-rotation of the bolt is prevented. Thereafter the cartridge is fired and the barrel and bolt begin to move rearwardly in recoil in the receiver, thus clearing the tongue 306 of the recess 310. Simultaneously the cam surface 320 of the cam 286 strikes the cam surface 321 in the receiver which returns the cam 286 to the groove 292 by causing rotation thereof. Rotation of the cam 286 causes a corresponding rotation of the cam 284 so that the parts 280 and 282 again occupy such a position that the splines 276 are in line with the splineways 278. The barrel is stopped in its recoil by engagement with the abutment 50, but the bolt continues in recoil rearwardly. If the gun is in semi-automatic fire, the bolt is retracted after discharge by depressing the lever 296 to lift the tongue 306 out of the recess 310 and then the bolt is rotated by grasp-

12

ing the finger lever 316 to bring the splines into alignment with the splineways, whereupon the bolt may be retracted by rearward movement to a cocked position.

Extractor-ejector construction

As illustrated herein, Fig. 14, the forward end of the breech bolt is provided with an empty cartridge case extractor 322 in the form of a hook which is adapted to engage into the cannelure at the base of the cartridge to withdraw it from the cartridge chamber. As the cartridge is moved rearwardly by the breech bolt in recoil, it is ejected through an ejection port 324 in the right hand side of the receiver by an ejector 326, Fig. 14. The speed with which the cartridge case is withdrawn is considerable, and if a stationary ejector is employed, the abrupt stop caused by engagement of the case with the rigid ejector to cause it to tilt outwardly about the extractor hook imparts considerable strain thereto. This tends to rupture the extractor hook at its base, and hence a feature of this invention is to provide means for cushioning the shock in order to increase the life of the extractor. As shown, the ejector comprises a lever 328 pivoted at 344 in the receiver and has a rear end 332 which normally rides on the surface of the bolt. The lever 328 is provided at its forward end with a head 334 which is pivotally attached thereto at 336, and between this head and a shoulder 338 formed on the lever there are disposed coiled springs 340 and 342 set into holes 344 and 346 drilled in the lever. The lever 328 is so arranged that during recoil the lever will be cammed by engagement of its rear end 332 with a cam surface 333 near the forward end of the bolt which will depress head 334 to a point nearer the axis of the bolt at which point it will be in a position to properly intercept the base of the cartridge. To this end there is formed in the bolt a longitudinal slot 335 having a forward depressed portion 337 for receiving the lever in its depressed position near the axis of the bolt. Since the head is yieldably supported on the lever 328, the cartridge will not be brought to an abrupt stop but will be cushioned. This will, therefore, reduce the shock on the hook 322.

Firing pin construction

As heretofore related, the breech bolt is comprised of two sections 280 and 282, Fig. 15, and these sections have passages 348 and 350 therein which are in axial alignment. At the forward end of the bolt the passage 350 terminates in a reduced portion 352 between which and the passage there is an annular conical shoulder 354. Within the passages 348 and 350 there is slidably mounted a firing pin 356 having at its forward end a penetrating tip 358 which is adapted to be projected through the reduced passage 352 and a shoulder 360 adapted to seat against the shoulder 354. In order to hold the firing pin in a retracted position during forward movement of the breech bolt, so that it will not be projecting therefrom and hence cause a premature firing of the cartridge as the bolt is moving into breech-closing position, there is disposed in an enlarged portion of the passages 350 a spring 362 which surrounds the firing pin, bearing at one end against an annular shoulder 364 in the passage and at its opposite end against an annular shoulder 366 formed on the firing pin. Since the breech bolt moves at relatively high speeds there is considerable momentum imparted to the firing

pin, and when the breech bolt is brought to a sudden stop just before it is rotated into locking position, the firing pin may, because of its momentum, be projected forwardly within the passages in spite of the resistance of the spring 362 so as prematurely to fire the cartridge. To prevent this there is formed in the firing pin a slot 368 into which projects a pin 370, the latter being fixed in the wall of the section 280. As constructed, the slot 368 will prevent the firing pin from moving through the opening 352 as long as the parts 280 and 282 occupy the relation to each other shown in Fig. 15, that is, in their fully extended position. When, however, the bolt is moved into breech-closing position and the forward portion thereof has been rotated to locking position, the effective length of the two parts is reduced so that thereafter the firing pin may be moved to such a position that the penetrating tip 358 may be projected beyond the end of the bolt and hence to penetrate the primer of the cartridge.

It should be understood that the present disclosure is for the purpose of illustration only and that this invention includes all modifications and equivalents which fall within the scope of the appended claims.

I claim:

1. A rapid-firing gun of the type in which the barrel moves in recoil and counter-recoil comprising a receiver, a barrel slidable therein, a breech and cartridge chamber associated with said barrel and movable therewith, a bolt chamber in said receiver, a breech bolt movable in the bolt chamber for closing the breech, a detachable cartridge belt feed mechanism housing situated below the bolt chamber, said housing being downwardly removable from the bolt chamber together with the cartridge belt to clear the gun of both the feed mechanism and cartridge belt said housing having an opening in one side bordered by a smooth lip over which may be drawn a freely suspended belt of cartridges for entrance into said housing, means releasably locking said feed mechanism housing to the receiver, said bolt chamber having an opening in its lower wall communicating with the cartridge belt feed mechanism housing through which the cartridges entering into the housing may project into the bolt chamber, feeding means for drawing the freely suspended belt over the lip into the housing and advancing cartridges one at a time into a position therein in which the top of the leading cartridge projects through said opening into the path of the breech bolt, and actuatable means for effecting operation of the feeding means in timed relation with the movement of the breech bolt to feed a cartridge into said position ahead of the bolt, said last-named means being actuated by the recoil of the barrel.

2. A rapid firing gun according to claim 1 wherein there is a shoulder on said barrel, and means interposed between said shoulder and said cartridge-feeding means forming an operative connection between the two to impart feeding movement to the cartridge-feeding means upon recoil of the barrel.

3. A rapid-firing gun of the type in which the barrel moves in recoil and counter-recoil comprising a receiver, a barrel slidable therein, a breech and cartridge chamber associated with said barrel and movable therewith, a bolt chamber in said receiver, a breech bolt movable in the bolt chamber for closing the breech, a cartridge feed mechanism housing below the bolt

chamber, said housing having a side opening bordered by a smooth lip over which may be drawn a freely suspended belt of cartridges for entrance into the housing said bolt chamber having an opening in its lower wall communicating with the cartridge feed mechanism housing, through which cartridges entered into the housing may project into the bolt chamber means within the housing for drawing the belt over the lip into the housing and advancing cartridges one at a time into a position such that a portion of the cartridge projects through said opening into the path of the breech bolt, a shoulder on said barrel, a lug resting against said shoulder, said lug being a part of the feeding means, and spring means in the receiver urging the lug in a direction to hold the barrel in battery.

4. In a rapid-firing gun of the type in which the barrel moves in recoil and counter-recoil comprising a receiver, a barrel slidable therein, a breech associated with said barrel and movable therewith, a piston associated with the barrel, a cylinder associated with the receiver into which the piston slidably fits, an aperture extending through the barrel into the cylinder between the piston and the inner end of the cylinder, a shoulder on the barrel, a lug engaging the shoulder, a slide bar carried by the receiver to which the lug is fixed, yieldable means urging said slide bar in a direction to hold the barrel in battery, said slide bar being movable rearwardly by the recoil movement of the barrel, a cartridge feeder operable to supply cartridges one at a time to a position to be charged into the cartridge chamber, and means connecting said cartridge-feeding means to the rear end of said slide bar for operation thereby.

5. In combination with a firearm of the recoil-barrel type, a receiver, a barrel movable in recoil and counter-recoil therein, a breech and cartridge chamber associated with the barrel and movable therewith, a bolt chamber in said receiver adjacent to said breech, a bolt movable in said bolt chamber in recoil and counter-recoil, a feed mechanism housing below said bolt chamber having lateral openings at opposite sides thereof through which a cartridge belt of the disintegrating type is adapted to be moved to present one cartridge at a time into a position below the bolt chamber, and means for feeding the cartridge belt into said feed mechanism housing from one side, said means comprising a pair of feed pawls operable successively to engage the under side of a cartridge and push it into said position, and means effected by the recoil of the barrel for operating said pawls.

6. In combination with a firearm of the recoil-barrel type, a receiver, a barrel movable in recoil and counter-recoil therein, a breech and cartridge chamber associated with the barrel and movable therewith, a bolt chamber in said receiver adjacent to said breech, a bolt movable in said bolt chamber in recoil and counter-recoil, a feed mechanism housing below said bolt chamber having lateral openings at opposite sides thereof into which a cartridge belt is moved to present one cartridge at a time into a position below the bolt chamber, and means for feeding the cartridge belt into said feed mechanism housing from one side, said means comprising pairs of feed pawls arranged successively to engage and push a cartridge into position, one of said pairs of pawls being retracted beneath the succeeding cartridge as the other pair advances the preceding cartridge, and means effected by the recoil of the barrel for operating said pawls.

7. In combination with a firearm of the recoiling barrel type, a receiver, a barrel movable in recoil and counter-recoil therein, a breech and cartridge chamber associated with the barrel and movable therewith, a bolt chamber in said receiver adjacent to said breech, a bolt movable in said bolt chamber in recoil and counter-recoil, a feed mechanism housing below said bolt chamber having lateral openings at opposite sides thereof into which a cartridge belt of the disintegrating type is adapted to be moved to present one cartridge at a time in the feed mechanism housing below the bolt chamber in a position to be rammed into the cartridge chamber, and means for feeding the cartridge belt into said feed mechanism housing from one side, said means comprising pairs of feed pawls arranged successively to engage and push a cartridge in two steps into said ramming position, the pawls being alternately retracted and advanced and being yieldable during retraction to pass beneath the cartridge being advanced by the advancing pair of said pawls, and means effected by the recoil of the barrel for operating said pawls.

8. In combination with a firearm of the recoiling barrel type, a receiver, a barrel movable in recoil and counter-recoil therein, a breech and cartridge chamber associated with the barrel and movable therewith, a feed mechanism housing chamber inside the receiver adjacent to said breech, said feed mechanism housing chamber having lateral openings at opposite sides thereof into which a cartridge belt of the disintegrating type is adapted to be moved to present one cartridge at a time into a position to be rammed into the cartridge chamber, and means for feeding the cartridge belt into said feed mechanism housing chamber, said means comprising pairs of feed pawls, a movable support for holding said feed pawls in an operative position, said pawls being yieldable on the support, means operable to oscillate said feed pawls on said support simultaneously to advance one pair and retract the other pair, said means being operated by the recoil of the barrel, and means for moving the support in a direction to withdraw the feed pawls to an out of the way position.

9. In combination with a firearm of the recoiling barrel type, a receiver, a barrel movable in recoil and counter-recoil therein, a breech and cartridge chamber associated with the barrel and movable therewith, a feed mechanism housing chamber inside the receiver adjacent to said breech, said feed mechanism housing chamber having lateral openings at opposite sides thereof into which a cartridge belt of the disintegrating type is adapted to be moved to present one cartridge at a time into a position to be rammed into the cartridge chamber, and means for feeding the cartridge belt into said feed mechanism housing chamber, said means comprising pairs of feed pawls, a support in said feed mechanism housing for said feed pawls, means for holding the support in an operative position in which said feed pawls engage the cartridges, means on the support operable to oscillate said feed pawls simultaneously to advance one pair and retract the other pair, said means being operable by the recoil of the barrel, yieldable means between the feed pawls and their support to permit depression during retraction, and means for removing the support from an operative to an inoperative position to withdraw the feed pawls from the cartridge belt and for locking it in its inoperative position.

10. In combination with a firearm of the re-

5 coiling barrel type, a receiver, a barrel movable in recoil and counter-recoil therein, a breech and cartridge chamber associated with the barrel and movable therewith, a feed mechanism housing chamber mounted on the receiver means releasably locking the feed mechanism to the receiver below said breech at the underside of the gun, said housing being releasably fastened to said receiver, said feed mechanism housing chamber having lateral openings at opposite sides thereof into which a cartridge belt of the disintegrating type is adapted to be moved, a ramp in the feed mechanism housing chamber directly below the breech bolt, said ramp having a cartridge-receiving surface the forward part of which is upwardly inclined and recessed longitudinally to cradle the small end of the cartridge and a rear end which is flat to permit uninterrupted sliding movement of the cartridge belt and bore of the cartridge thereacross, means yieldably urging said ramp toward an elevated position, means in said feed mechanism housing chamber for feeding the cartridge belt into the chamber comprising pawls arranged to engage successive cartridges and push them one at a time onto the ramp by depression thereof, said ramp thereafter holding said cartridge elevated in the path of the bolt, and means for oscillating the pawls to effect feeding movement thereof, said means being actuated by the recoil of the barrel.

11. In combination with a firearm of the recoiling barrel type, a receiver, a barrel movable in recoil and counter-recoil therein, a breech associated with the barrel and movable therewith, a bolt and the bolt chamber in the receiver behind the breech, a feed mechanism housing chamber below the bolt chamber at the underside of the gun, opening into the bolt chamber, said opening being narrower than the diameter of the cartridge, an elevator in the magazine chamber below the bolt chamber, said housing being releasably attached to the receiver, means releasably locking the feed mechanism to the receiver, said elevator having a transversely horizontal cartridge-receiving surface surmounting downwardly inclined surfaces at opposite sides thereof forming an approach for the line charge to the horizontal surface and a discharge for the empty case from said surface, said top surface having a substantially flat rear portion over which the belt and base of the cartridge may slide uninterrupted and an upwardly inclined forward portion recessed to cradle the small end of the cartridge, means yieldably pressing said elevator towards said opening to hold a cartridge resting thereon against said opening, with a portion thereof projecting through the opening, and means in said chamber to feed cartridges one at a time onto the elevator between it and the openings, said means being actuated by the recoil of the barrel.

12. In combination with a firearm of the recoiling barrel type, a receiver, a barrel movable in recoil and counter-recoil therein, a breech and cartridge chamber associated with the barrel and movable therewith, a feed mechanism housing chamber removably mounted in the receiver, feed mechanism in said feed mechanism housing chamber adapted to feed cartridges one at a time to a position therein to be rammed into the cartridge chamber, said feed mechanism being operated by the recoil of the barrel, connecting means for coupling the feed mechanism to the barrel for operation of the former solely by

mounting the magazine in the receiver, supporting elements on said receiver slidably engaging cooperable supporting elements on the feed mechanism housing, and means for releasably locking the feed mechanism housing in the receiver.

13. In combination with a firearm of the recoiling barrel type, a receiver, a barrel movable in recoil and counter-recoil therein, a breech and cartridge chamber associated with the barrel and movable therewith, a feed mechanism housing chamber removably mounted in the receiver, feed mechanism in said feed mechanism housing chamber adapted to feed cartridges one at a time to a position therein to be rammed into the cartridge chamber, said feed mechanism housing chamber comprising a two-part housing hinged along one edge, the lower part being swingable downwardly with respect to the upper part to expose the feeding mechanism, and latch means for locking the lower part to the upper part.

14. In combination with a firearm of the recoiling barrel type, a receiver, a barrel movable in recoil and counter-recoil therein, a breech and cartridge chamber associated with the barrel and movable therewith, a feed mechanism housing chamber removably mounted in the receiver, feed mechanism in said feed mechanism housing chamber adapted to feed cartridges one at a time to a position therein to be rammed into the cartridge chamber, said feed mechanism housing chamber comprising a two-part housing hinged along one edge, the lower part being swingable downwardly with respect to the upper part to expose the feed mechanism, a shoulder in the upper part, a latch pivoted to the lower part, spring means for urging the latch in a direction to engage the shoulder when the parts are closed to lock them closed, and a lever, a portion of which is exposed below the lower part operable to disengage the latch from said shoulder.

15. In combination with a firearm of the recoiling barrel type, a receiver, a barrel movable in recoil and counter-recoil therein, a breech and cartridge chamber associated with the barrel and movable therewith, a breech bolt in said receiver to which cartridges are delivered into a position to be rammed into the cartridge chamber by the bolt, feeding mechanism for delivering cartridges to said position for ramming into the cartridge chamber, said feeding mechanism including a housing releasably attached to the underside of the receiver below the cartridge chamber, means releasably locking the feed mechanism to the receiver, said feed mechanism housing comprising an open-sided throat section having a flared entrance and a subjacent closed housing section into the throat section, means for operating the feed pawls in the housing section to advance a cartridge into the throat section, means for withdrawing the feed pawls from the throat section into the housing section to clear the same, and means projecting through the top of the throat section to oppose retrogression of the cartridge belt by reason of its weight when said feed pawls have been retracted, said means being retractable to permit removal of the belt from the throat.

16. In combination with a firearm of the recoiling barrel type, a receiver including a stock,

a barrel movable in recoil and counter-recoil on the receiver, a breech and cartridge chamber associated with the barrel and movable therewith, a feed mechanism housing chamber mounted below the bolt chamber at the underside of the gun adjacent to said breech, said stock and receiver having spaced portions between which the housing is mounted in which are horizontal grooves, and said housing having forwardly and rearwardly extending lugs for engagement with said grooves, and means on the receiver and stock for preventing lateral movement of the lugs within the grooves.

17. In combination with a firearm of the recoiling barrel type, a receiver including a stock, a barrel movable in recoil and counter-recoil on the receiver, a breech and cartridge chamber associated with the barrel and movable therewith, a feed mechanism housing chamber mounted below the bolt chamber at the underside of the gun adjacent to said breech, said receiver having a depending lug in which there is a horizontal groove and said stock having a horizontal groove opposite the groove in said receiver, forwardly and rearwardly extending lugs on the housing for engagement with said grooves, and a bail pivoted on the receiver adapted to embrace the lug so as to cover the ends of the groove.

18. In combination with a firearm of the recoiling barrel type, a receiver including a stock, a barrel movable in recoil and counter-recoil on the receiver, a breech and cartridge chamber associated with the barrel and movable therewith, a feeding mechanism housing chamber mounted below the bolt chamber at the underside of the gun adjacent to said breech, said housing having rearwardly and forwardly projecting lugs, said rearwardly projecting lugs including a horizontal tongue and spaced vertical flanges, said stock having a portion thereof adapted to abut the housing between said spaced vertical flanges and a horizontal groove with which the tongue is adapted to be engaged, and said receiver having a horizontal groove with which the forward lug is adapted to be engaged, and a locking element pivoted on the receiver for movement over the open ends of the grooves in the receiver.
